UNITED STATES PATENT OFFICE.

ANDREW RASMUSSEN, JR., OF SALT LAKE CITY, UTAH.

COMBINED PHONOGRAPH AND PICTURE-PROJECTOR.

1,390,640.

Specification of Letters Patent. Patented Sept. 13, 1921.

Application filed March 8, 1921. Serial No. 450,541.

To all whom it may concern:

Be it known that I, ANDREW RASMUSSEN, Jr., a citizen of the United States, residing at Salt Lake City, in the county of Salt

5 Lake, State of Utah, have invented a new and useful Combined Phonograph and Picture-Projector; and I do hereby declare the following to be a full, clear, and exact description of the invention, such as will enable others skilled in the art to which it appertains to make and use the same.

The invention relates to combined phonographs and picture projectors and has for its object to provide a device of this character, 15 wherein a song which is being played will be illustrated by intermittently changing pictures, which pictures are projected on to the front of the cabinet of the phonograph.

A further object is to provide a sound 20 reproducing machine and picture projecting machine, said pictures being carried by leaves of a book, which leaves and book are mounted on a removable slide disposed over the amplifier and are intermittently changed 25 through mechanism coöperating with notches in the edges of the leaves and controlled by the tone arm; also to provide means whereby the pictures will be projected through the forward end of the amplifier on to a glass 30 in the front end of the amplifier.

A further object is to provide a book holder comprising a horizontally disposed member having adjacent its rear side horizontally disposed arms adapted to receive 35 and hold the rear edge of the book against the spring action of the book when it is bent to a vertical position against a vertically disposed spring. Also to provide vertically movable fingers for engaging the faces of the

40 leaves of the book, said fingers being moved by the tone arm in such a manner that they will register with stepped notches in the leaves of the book and intermittently release said leaves thereby allowing them to move to 45 a horizontal position for changing the picture. Also to provide a pivoted restoring bail whereby said leaves may be restored to vertical position.

With the above and other objects in view 50 the invention resides in the combination and arrangement of parts as hereinafter set forth, shown in the drawings, described and claimed, it being understood that changes in the precise embodiment of the invention may

be made within the scope of what is claimed 55 without departing from the spirit of the invention.

In the drawings:—

Figure 1 is a side elevation of the combined phonograph and picture projecting 60 machine, parts being broken away to more clearly illustrate the structure.

Fig. 2 is a vertical transverse sectional view taken on line 2—2 of Fig. 1 showing the restoring bail in vertical position. 65

Fig. 3 is a front elevation of the combined phonograph and picture projecting machine.

Fig. 4 is a detail perspective view of the tone arm controlling lever for controlling 70 the mechanism for intermittently changing the picture.

Fig. 5 is a top plan view of the removable slide which supports the book.

Fig. 6 is a perspective view of the book. 75

Fig. 7 is a perspective view of one of the leaves of the book.

Referring to the drawings, the numeral 1 designates the cabinet of a conventional form of phonograph thereof and 2 the turn 80 table thereof which may be operated by any form of spring motor. Disposed over the turn table 2 is a conventional form of tone arm 3 provided with a silas 4, which silas coöperates with the sound groove of the record 5 disposed on the turn table 2. Extending downwardly at the rear end of the cabinet 1 and in communication with the tone arm 3 is an amplifier 6, said amplifier having its lower end extending outwardly and upwardly and terminating in registration with a screened opening 7 in the front side 8 of the cabinet. 85

Disposed above within the cabinet and above the amplifier 6 is a horizontally disposed platform 9 having guide channels 10 transversely disposed, said guide channels being adapted to receive a slide 11 on which slide, a book 12 having a plurality of leaves provided with various pictures, illustrating the particular record being placed is disposed and held, said book being flexible at 13, thereby allowing the body of the book to be vertically disposed when its rear side 14 is forced under the clips 15 carried by the slide 11. The slide 11 is also provided with an upwardly extending spring arm 16 which engages the rear side of the book 12 and 100 105

exerts a forward pressure on the body thereof, the reason for which will presently appear. Extending upwardly and from points adjacent the ends of the slide 11 are vertically disposed guide rods 17, on which guide rods, the eyes 18 of a yoke 19 are guided in their upward and downward movement, said yoke being also guidable in its upward and downward movement by the eye 20 carried by 5 the horizontal portion 21 of the yoke, which eye is slidably mounted on the centrally disposed and vertically disposed rod 22, carried by the connecting rod 23 between the upper ends of the rods 17. It will be seen that the 10 yoke 19 will be guided in a vertical plane in such a manner that it will not bind on the guide rods. The eyes 18 terminate in inwardly extending fingers 24 which overlie the opposite vertical edges of the pages 25 15 of the book, which edges are provided with stepped notches 26, which when the fingers 24 are moved downwardly and come into registration with the notches of the pages allow the pages to be intermittently released, 20 thereby allowing the same to assume horizontal positions under their flexing action and under the initial impulse given the page by the upwardly extending spring 16 which bears against the back of the book. Also 25 disposed on the slide 11 and to each side of the book 12 are electric lights 27, which lights reflect and project the picture on the leaf of the book which is exposed through the lens 28 in the housing 29 of the forward 30 portion of the amplifier 6 and on to the frosted glass 30 supported in the screened opening in the front side 8 of the cabinet of the graphophone. Pivotedly mounted and transversely disposed on the slide 11 is a rockable 35 shaft 31 having a centrally disposed bail 32, which bail is normally in horizontal position as shown in Fig. 1, and disposed beneath the leaves as they are intermittently released by the fingers 24. After the leaves 40 have been released said leaves may be restored to their vertical position as shown in Fig. 1 by the operator opening the door 33 in the side of the cabinet and grasping the thumb member 34 in such a manner that the 45 shaft 31 may be rotated and the bail 32 forced upwardly in engagement with the leaves until the leaves are vertically disposed as shown in Fig. 1.

Secured to the upper side of the yoke 19 50 as at 35 is a cord 36, which cord extends over a pulley 37 carried by the upper end of the post 22 and thence over a pulley 38 carried by an inwardly and outwardly adjustable screw 39. The cord 36 after passing over the pulley 38 extends inwardly and is connected as at 40 to a pivoted lever 41, said pivotal lever having its pivotal point 42 substantially centrally thereof and its arm 43 extending upwardly through the casing and terminating in a bifurcation 45,

which bifurcation receives the lower end 46 of a pin 47 carried by the tone arm 3. Pin 47 moves with the tone arm 3 and it will be seen that as the tone arm moves inwardly during the playing of a record that the lever 41 will be rocked on its pivotal point thereby allowing the yoke 19 to move downwardly for intermittently releasing the pages 25 of the book thereby showing various scenes and illustrating the song that is 75 being played. It will be seen that by adjusting the screw 19 that the pictures may be synchronized with the music. It will also be seen that when the tone arm 3 is restored to starting position as shown in Fig. 80 2, that the yoke 19 will also be raised to starting position.

From the above it will be seen that a combined phonograph and picture projecting machine is provided which is simple in construction and one wherein the operation is positive and the parts reduced to a minimum.

The invention having been set forth what is claimed as new and useful is:—

1. A combined phonograph and picture projector comprising a rotatable disk, a tone arm movable adjacent said disk, said tone arm terminating in a downwardly and outwardly extending amplifier, the outer end 90 of said amplifier curving outwardly, a vertically disposed lens carried in a housing of said amplifier and in alinement with a screen disposed in the amplifier end, a plurality of pictures disposed behind the lens 100 and means for intermittently changing said pictures, said means being controlled by the tone arm.

2. A combined phonograph and picture projector comprising a rotatable disk, a tone 105 arm movable adjacent said disk, said tone arm terminating in a downwardly and outwardly extending amplifier, the outer end of said amplifier curving upwardly, a vertically disposed lens carried in a housing of 110 said amplifier, a screen disposed in the amplifier end and in alinement with the lens, a plurality of pictures disposed behind the lens, means for intermittently changing said pictures, said picture changing means being 115 controlled by the tone arm and means for varying the time of change of the pictures.

3. The combination with a phonograph comprising a rotatable disk having a tone arm movable adjacent said disk and a downwardly, outwardly and upwardly extending amplifier, of means controlled by said tone arm for intermittently releasing a plurality of members having pictures thereon whereby said pictures may be projected on a 120 screen, said means comprising a vertically movable yoke having a flexible connection with the tone arm, said yoke being provided with fingers co-operating with the edges of the picture carried members and adapted to 125 130

be moved into registration with notches in the edges of said members for intermittently releasing said members.

4. The combination with a phonograph comprising a record, a tone arm, a downwardly and forwardly extending amplifier, of a book support and picture projecting device therefor controlled by the tone arm, said device comprising a platform arching the amplifier and transversely disposed, vertically disposed rods carried by said platform, a yoke slidably mounted on said rods and provided with inwardly extending fingers, a book held on said platform and having its pages provided with non-registering notches, a flexible member connected to the upper end of the yoke and passing over pul-
- 10
- 15

leys, said cable having its upper end connected to a pivoted lever, connecting means between the pivoted lever and the tone arm 20 whereby during the playing of a record, the yoke will slowly move downwardly, means for projecting the pictures on the pages of the book on a screen and means whereby as the yoke moves downwardly said leaves of 25 the book will be intermittently released and allowed to move to a horizontal position.

In testimony whereof I have signed my name to this specification in the presence of two subscribing witnesses.

ANDREW RASMUSSEN, JR.
